UNITED STATES PATENT OFFICE.

JAMES HUGH BROWN, OF BUTTE, MONTANA.

GRATE.

1,280,151.

Specification of Letters Patent.

Patented Oct. 1, 1918.

Application filed April 12, 1917. Serial No. 161,423.

To all whom it may concern:

Be it known that I, JAMES H. BROWN, a citizen of the United States, and a resident of Butte, in the county of Silverbow and 5 State of Montana, have invented a certain new and useful Improvement in Grates, of which the following is a specification.

One of the principal objects of my invention is to provide an improved grate in 10 which perforated plates are removably supported on base frames in such manner as to be individually removable for renewal or repair, the construction being such that there is a free circulation of air through and 15 around the plates.

Another object of the invention is to provide an improved grate of the class described, which will be extremely simple, durable, efficient in operation, and inexpensive 20 to manufacture.

With these and other objects in view which will become apparent as the description proceeds, the invention resides in the construction, combination, and arrangement 25 of parts hereinafter more fully described and claimed, and illustrated in the accompanying drawings in which like characters of reference indicate like parts throughout the several figures, of which—

30 Figure 1 represents a top plan view of a section of grate constructed according to my invention;

Fig. 2 represents a side elevational view thereof;

35 Fig. 3 represents a view in section taken on the plane indicated by the line 3—3 of Fig. 1;

Fig. 4 represents a view in perspective of one of the plates looking at the under side 40 thereof;

Fig. 5 represents a sectional view taken vertically and transversely through a couple of forced draft burner pans of special design, having the base frame and plates constructed according to my invention mounted thereon;

Fig. 6 represents an enlarged fragmentary side elevational view of the device.

Fig. 7 represents a view similar to Fig. 3 50 showing the arrangement when the flanges project outwardly from the bars.

Referring more particularly to the drawing, I have shown in Figs. 1 to 3 inclusive, for the purpose of convenience in illustration, base frames or grate bars of rectangular shape, including the side bars 5, front

end blocks 6, rear end blocks 7, and spaced transverse braces 8 connecting the side bars 5 together intermediate their ends.

Each of the base frames supports a series 60 of removable plates thereon. These plates are preferably rectangular in shape, and are indicated at 10, being of a width somewhat greater than the width of the base frames, and each plate is provided with a plurality 65 of oblong perforations 4 upwardly through which air may readily pass. If found to be desirable, the openings 4 may be of some other shape and may be arranged in various different ways.

70 Each of the plates 10 is provided with oppositely extending pairs 11 and 12 respectively, of guide lugs. These lugs are arranged inwardly from the lateral edges of the plates, and the outer ends of the lugs are 75 undercut or beveled as at 13 to slidably engage the inwardly projecting beveled flanges 14 formed on the upper edges of the lateral bars 5 of the base frames. Between the lugs for a suitable distance, the material on the 80 under face of each block is cut away as at 15 to leave pads 15^a forming an air space between the upper edges of the bars 5 and the under faces of the blocks as clearly indicated in Fig. 3. The cut away portions 15 85 are of such width as to extend inwardly of the inner edges of flanges 14, so that the air may freely pass up over the top edges of bars 5. At their end edges the plates 10 are recessed as at 16, so that when they are 90 in assembled position upon the base frames, air openings will be formed between the abutting ends of the plates.

At a suitable distance from their forward ends the opposed bars of each frame are 95 provided with recesses 17 cut in the flanges 14 whereby to admit of the guide lugs, formed on the plates, being passed downwardly to aline with the flanges 14, as will be understood. In this manner the blocks 100 may be readily engaged one after another upon the lateral bars of the base frames in position to be slid longitudinally of the frames into their desired positions.

By having the blocks thus slidably and 105 detachably engaged upon the base frames, it will be understood that any certain one or more of the blocks may be readily removed for renewal or repair.

The base frames are preferably arranged, 110 as indicated in Fig. 1, at suitable distances apart to allow a space 18 between the adj-

cent edges of the series of plates, for the circulation of air. To obtain a uniform space between the series of blocks throughout the grate, the front end blocks 6 of the base frames are preferably extended slightly beyond the lateral edges of the frames, as indicated in Fig. 1, so that when they abut, the proper space between the series of blocks will have been attained.

10 The arrangement shown in Fig. 5 is that followed when the grate is adapted for use in connection with a forced draft burner pan of a particular type. Here the lower edges of the bars 5 of the base frame are beveled as at 19 to fit in the recesses 20 formed in the upper edges of the burner pan walls.

While the rectangular plates serve to conveniently illustrate the invention, it is to be understood that the plates will in actual practice be made in various shapes and contours to conform in shape with any shape grate bars in connection with which the invention is to be used.

25 The beveled flanges 14 formed on upper edge of the lateral bars 5 of the base frame may project outwardly, as well as inwardly.

As shown in Fig. 7, the beveled flanges on the upper edges of the base frame bars 30 may project outwardly and in this instance the lugs on the plates will be beveled or undercut at their inner ends as shown so as to slidably fit on the flanges.

Although I have described the preferred 35 embodiment of my invention, I may desire to make such changes in the construction, combination, and arrangement of parts thereof, as do not depart from the spirit of the invention or the scope of the appended 40 claims.

I claim:—

1. A grate including a base frame consisting of spaced walls having flanges at the upper edges, the flanges having cutout

portions at one extremity of the base frame, 45 a plurality of plates supported on the walls, lugs formed on the bottom of each plate, engageable with the flanges to hold the plates in place, the lugs entering the cutout portions when the plates are put in place, and 50 a pad formed on the bottom of each plate including portions adjacent to the lugs extending beyond the main pad portion and adapted to rest on the edges of the walls to space the plate from said edges and provided 55 an air passage.

2. A grate including a base frame having spaced side walls with continuous beveled flanges disposed longitudinally of the upper edges, recesses being cut out of the 60 flanges near one extremity of the base frame, a plurality of plates arranged to be supported by the base frame, lugs formed beneath each plate adapted to enter the recesses and be slid in position engaging the 65 longitudinal flanges, and pads formed in the middle of each plate between the lugs and plate, to leave spaces for air passage when the said pads rest upon the side walls 70 of the base frame.

3. A grate including a plurality of base frames, each consisting of spaced walls having front end blocks extending beyond the sides of the walls ending at spaces between the base frame and providing an air passage, a plurality of plates arranged to be slid into position upon each base frame from a place at the front end blocks, holding means carried by the blocks and engaging the side walls, engaging lugs on the lateral 75 edges of each plate providing an air passage, and pads on the bottoms of the plates spacing the plates from the top of the walls to provide an air passage.

JAMES HUGH BROWN.
